UNITED STATES PATENT OFFICE.

BENJAMIN F. HUMPHREY, OF BOSTON, MASSACHUSETTS.

BOOK-SAWING MACHINE.

SPECIFICATION forming part of Letters Patent No. 285,123, dated September 18, 1883.

Application filed March 9, 1883. (No model.)

To all whom it may concern:

Be it known that I, BENJAMIN F. HUMPHREY, of Boston, in the county of Suffolk, State of Massachusetts, have invented a certain new and useful Improvement in Book-Sawing Machines, of which the following is a description sufficiently full, clear, and exact to enable any person skilled in the art or science to which said invention appertains to make and use the same, reference being had to the accompanying drawings, forming a part of this specification, in which—

Figure 1 is an isometrical perspective view of my improved machine; Fig. 2, a top plan view; Fig. 3, a view showing the method of attaching the saw; Fig. 4, a perspective view of a book after having been sawed for binding; Fig. 5, a vertical transverse section taken on the line *x*, Fig. 1; and Fig. 6, a top view of the auxiliary or sliding table.

Like letters of reference indicate corresponding parts in the different figures of the drawings.

My invention relates to that class of sawing machines which are used by book-binders for sawing the folds or backs of books, or for making the cuts to receive the twines or tapes forming the bands used in binding; and it consists in a novel construction and arrangement 30 of the parts, as hereinafter more fully set forth and claimed, by which a more desirable and effective article of this character is produced than is now in ordinary use.

The nature and operation of the improvement will be readily understood by all conversant with such matters from the following explanation, its extreme simplicity rendering an elaborate description unnecessary.

In the drawings, A represents the frame-work, B the treadle, and C the table.

Mounted in the upper part of the frame-work and fitted to slide vertically in the ways *d d* there is a frame or gate, D, carrying a gang of vertically-arranged saws, *m*. These saws are secured to stocks or carriers *a* by means of screws 15, inserted, respectively, at their upper and lower ends, the backs of the saws abutting against a rabbet or shoulder, 16, their serrated edges being arranged to project in front of the stocks, as shown in Fig. 3.

A horizontal T-shaped slot, *f*, is formed in

either end of the frame D, this slot opening outwardly, or toward the saws; and passing through each of the stocks *a* there is a bolt, *b*, provided at its outer end with a thumb screw or nut, *g*, and at its inner end with a head, *i*, the heads of the bolts being fitted to work in the T-shaped slots *f*, and the bodies of the bolts passing outwardly through said slots and through the stocks *a*, as best seen in Fig. 5.

Attached to one side of each of the saws *m* there is a vertical strip, *v*, these strips being made laterally-adjustable on the saws by bolts and nuts *h*, the bolts passing through horizontal slots *z*, formed in the strips for this purpose.

The treadle B is pivoted at its inner end to the horizontal rod H, mounted in the lower part of the frame A, and is connected to the frame D by means of the sliding pitman-rod J and oscillating pitman K, the upper end of the rod K being jointed at *y* to the rod J, and at its lower end, at *l*, to the treadle B. The rod J is provided with a coiled spring, L, the lower end of the spring resting on the cross-bar M of the frame A, and its upper end abutting against the lower side of the collet N, the collet being rendered vertically adjustable on the rod by the screw *p* in such manner as to obtain any desired tension on the spring, the object of the spring being to elevate the treadle B and frame D when the machine is worked by foot-power. A joint, *n*, connects the rod J with the frame D, the rod passing through a vertical hole in the bar M, and being provided beneath said bar with an adjustable stop-collet, R, carrying the rubber washer *q*.

A table, C, supported on the brackets 17, is arranged in front of the saws, this table carrying an auxiliary table, 18, which is fitted to slide horizontally on the ways 19, and slotted at its inner edge, 20, to receive the saws *m*. The table C is provided with adjustable stops 21, against which the shoulders 22 on the auxiliary table strike to prevent it from coming into contact with the saws, the gages being also designed to determine the depth of the cuts in the book.

The stocks or carriers may be provided with either one or two saws each, in accordance with the work being done; but it is preferable

to have but one saw attached to the outer holder in the gang, as these make the kettle-band cuts *r*, which are usually somewhat separated from the body-cuts *t* in the back of the book.

In the use of my improvement for light work the gage-strips *v* are first adjusted on the saws *m* by means of the nuts and bolts *h* being brought forward toward the teeth or moved 10 back toward the backs of the saws, in accordance with the depth of the cuts to be made in the back of the book. After the gage-strips have been properly adjusted, the saws carrying the strips are next adjusted in the frame or 15 gate *D* by means of the nuts and bolts *g b*, being spaced in accordance with the location of the cuts to be made in the back of the book, or, for instance, as shown in Fig. 4, the outer saws in the gang making the kettle-band or 20 end cuts, *r*, and the central saws the body-cuts *t*. When the saws have been properly adjusted, as described, the auxiliary table 18 is removed, and the folds composing the book *E* are inserted between two clamps or boards, 25 *w*, and placed on the table *C*, the book projecting slightly from between the clamps at their inner edges, both of the tables being cut out to enable the clamps to be grasped firmly in the hands of the workman running the machine, as seen at *T* in Fig. 1. The foot of the workman is then placed on the treadle *B*, and the treadle worked to give a vertical reciprocating movement to the saws, the book being 30 at the same time fed or pushed forward until it strikes the gage-strips *v*, and the cuts *r t* are made in a manner which will be readily obvious without a more explicit description.

When the machine is used on heavy work, the auxiliary table 18 is employed, the strips 40 *v* being set back out of the way or removed entirely, and the stops 21 used to gage the cut of the saws.

Two vertically-arranged stops, 24, are secured to the inner edge of the auxiliary table, 45 against which the work is "jogged" or the folds of the book adjusted preparatory to sawing the cuts, as this part of the process cannot be readily performed on heavy work without injuring the saws when the saws are used 50 as gages for jogging or adjusting the folds, as in light work. A gage, *P*, is also attached to the auxiliary table, and made adjustable thereon by the screws 25, a similar gage (not shown) being used on the table *C* when the table 18 is 55 removed.

It will be obvious that the treadle may be dispensed with and the machine driven by power, if desired, and for this purpose I have provided the hanger *Q*, in which to mount a 60 shaft, which may be connected in any suitable manner with the rod *J*.

It will also be obvious that any number of the saws *m* may be employed, and that the gages *v* or stops 21 may be set to govern the depth of the cuts as desired.

65

I do not confine myself to making the saws laterally adjustable in the frame *D* by means of the slots *f*, stocks *a*, and nuts and bolts *g b*, as this may be accomplished by other means. Neither do I confine myself to attaching the 70 gages *v* directly to the saws, although I deem this preferable, as they clamp and stiffen them and enable the machine to perform its work in a more perfect manner.

Having thus explained my invention, what 75 I claim is—

1. The improved book-sawing machine herein described, the same consisting of the frame *A*, provided with the table *C* and ways *d*, the frame *D*, mounted in said ways and provided 80 with the slots *f*, the saws *m*, secured to the stocks *a*, and provided with the adjustable gages *v* and nuts and bolts *g b*, the heads of said bolts working in the slots *f*, and the treadle *B*, rods *J K*, and spring *L*, all constructed, combined, and arranged to operate 85 substantially as set forth.

2. In a book-sawing machine, two or more laterally-adjustable saws mounted in a frame or gate and adapted to receive vertical reciprocating movements, a gage or gages for regulating the depth of the cuts to be made in the back of the book, and a table on which the book or folds of the book is supported while being sawed, in combination with means, substantially as described, for giving vertical reciprocating movements to the saws, substantially 95 as described.

3. In a book-sawing machine, the gages *v*, attached to and rendered adjustable on the 100 saws *m*, substantially as set forth.

4. In a book-sawing machine, the frame or gate *D*, provided with the slots *f*, in combination with the stocks *a*, nuts and bolts *g b*, saws *m*, and operative mechanism, substantially as 105 described.

5. The combination of a gang of saws, means for reciprocating the same, and a book-holding table provided on one side with a series of open slots adapted to receive the saws, and on 110 the other side with a recess to enable the workman to readily manipulate the book-clamps, substantially as described.

6. In a book-sawing machine, the stops 21, in combination with the table *C*, auxiliary table 115 18, and saws *m*, substantially as and for the purpose set forth.

BENJ. F. HUMPHREY.
